UNITED STATES PATENT OFFICE.

MARK E. HUNTER, OF ALLEGHENY, PENNSYLVANIA.

CLAMP FOR HOLDING PLATE-GLASS.

SPECIFICATION forming part of Letters Patent No. 737,109, dated August 25, 1903.

Application filed April 18, 1903. Serial No. 153,215. (No model.)

To all whom it may concern:

Be it known that I, MARK E. HUNTER, a citizen of the United States, residing at Allegheny, in the county of Allegheny and State 5 of Pennsylvania, have invented a new and useful Improvement in Clamps for Holding Plate-Glass, of which improvement the following is a specification.

This invention relates to certain new and 10 useful improvements in glass-clamps, and more particular to that class of clamps employed to support and hold plate-glass in windows, show-cases, and the like.

The object of my invention is to provide a 15 clamp which will allow a window-light to settle or adjust itself, at the same time giving sufficient rigidity to the glass to hold and support it in position.

Another object of my invention is to construct a clamp which will be simple in construction, comparatively inexpensive to manufacture, and highly efficient in operation.

Heretofore considerable trouble has been experienced in the cracking and breaking of 25 plate-glass on account of the settling or slight sagging of the same, the break in the glass often being due to the holes which have been drilled or filed in the glass to permit the clamping of the glass together, and it is one 30 of the main and essential features of my clamp that the drilling of holes in the glass is entirely dispensed with.

With the above and other objects in view reference will be had to the accompanying 35 drawings, in which like letters of reference indicate like parts throughout the several views of the drawings, in which—

Figure 1 is a perspective view of my improved clamp. Fig. 2 is a top plan view. 40 Fig. 3 is a rear view of the body portion with the clamp removed. Fig. 4 is a detail of one of the clips. Fig. 5 is a fragmentary view of one of the clips in position, the shield being broken away; and Fig. 6 is a perspective view 45 of the shank of the clamp.

To put my invention into practice, I provide a strip of any suitable metal 1, said strip being formed at an angle suitable to the angle at which the glass is to be held, and in 50 the drawings I have shown the clamp formed nearly at a right angle. This metallic strip 1 has its ends enlarged, as indicated at 2, and

the rear faces of the sides 3 and 4 cut away, as shown at 5. The vertex formed by the sides 3 and 4 is cut away, as shown at 6, said 55 cut-away portion extending the width of the clamp, and in this cut-away portion is secured the shank 7, said shank being formed integral with a metallic strip 8, and upon the outer end of said strip is secured the screw- 60 threaded stem 9, and upon this stem is mounted the adjusting member 10, which clamps the glass 11 to the clamp proper, as indicated by the reference-numeral 1. The adjusting member 10 has its two extending ends 12 and 65 14 formed at an angle corresponding to the clamp proper, 1, and to secure and adjust the member 10 I provide a nut or top 15 upon the screw-threaded stem 9.

Mounted upon the rear faces 16 and 17 of 70 the sides 3 and 4, respectively, and adjustably seated in the cut-away portions 5 are the clips 18, said clips being slidably mounted upon the rear faces 16 and 17 by means of a lug 19, formed integral with the rear faces 16 and 17. 75 The clips 18 have slots 20, which engage over the lugs 19 and hold the clips from dropping from the cut-away portions 5. These clips are substantially the shape illustrated in Fig. 4 of the drawings, said clips having formed 80 near one end thereof a lug or stud 21, which engages in a depression or recess 21^X, formed in the inner faces of the glass to be clamped. The clips 18 are supported and held in position by spring-shields 22, said shields being 85 secured at their outer ends by any suitable means upon the rear faces 16 and 17, while their other ends project from the rear faces, as shown at 23, thus forming a spring-surface 90 upon which the glass bears. These shields 22 are cut away, as indicated at 24, to allow the lug 21 to project into the glass.

From the above description it will be seen that I have constructed my improved clamp in such manner as to allow the window to adjust itself to the conditions caused by windy weather and the jars and generally sagging of plate-glass. The edges of the glass resting against the metallic strip 8 gives support and rigidity to the same, and by the lugs 21 engaging the surface of the glass it is firmly held, at the same time allowing the glass sufficient movement to prevent it cracking or breaking.

Having fully described my invention, what I claim, and desire to secure by Letters Patent, is—

1. A clamp for plate-glass consisting of a body portion formed at any desired angle, said body portion being connected to an auxiliary clamp, by a movable shank, said auxiliary clamp being adjustable, adjustable clips carried by the body portion for engaging the plate-glass substantially as described.
2. A clamp for plate-glass consisting of a body portion and an auxiliary clamp, said body portion and clamp being connected by a movable shank, a screw-thread stem carried

by said shank and supporting the auxiliary clamp, adjustable clips carried upon the rear faces of the body portion lugs formed integral with said clips, spring-shields protecting and supporting said clips, substantially as described.

In testimony whereof I have hereunto signed my name in the presence of two subscribing witnesses.

MARK E. HUNTER.
